FOLDING MECHANISM FOR CARTONING MACHINES

Filed March 30, 1928

26 Inventor:
27 Arthur H. Boileau
By Wm O. Bell Atty

UNITED STATES PATENT OFFICE.

ARTHUR H. BOILEAU, OF CEDAR RAPIDS, IOWA, ASSIGNOR, BY MESNE ASSIGNMENTS, TO CHERRY-BURRELL CORPORATION, OF WILMINGTON, DELAWARE, A CORPORATION OF DELAWARE.

FOLDING MECHANISM FOR CARTONING MACHINES.

Application filed March 30, 1928. Serial No. 265,850.

This invention relates to folding mechanism for cartoning machines and particularly to mechanism which makes the last fold in a carton and tucks in the end flap tip. While the invention may be applied successfully to various types of cartoning machines it has been designed primarily for butter cartoning machines as disclosed and claimed in the copending application, Serial No. 255,004, filed February 17, 1928.

The object of the invention is to provide novel folding mechanism which will positively and accurately make the last fold in a carton and insert the end flap tip in proper and final position.

Another object is to provide novel folding mechanism which will insert the flap tips and press the end flaps into final position and assure that the inserting blade for guiding the flap tips will be cleanly withdrawn without damage to carton or its contents.

And a further object is to provide folding mechanism which is positive and efficient in operation, which is simple and durable in construction, and which can be readily and economically manufactured and easily installed on existing machines.

In the accompanying drawing illustrating a selected embodiment of the invention the views are as follows:

Fig. 1 is a detail elevation of the folding mechanism applied to a part of a cartoning machine.

Fig. 2 is a detail perspective view showing some of the parts in operating position.

Fig. 3 is a detail view of a carton partly folded.

Referring to the drawing, 5 designates a bridge which may be an integral part of the frame of a cartoning machine, or it may be made in a separate unit and fixed to the frame. A rocker arm 6 is pivoted to the bridge at 7 and this rocker arm has a pair of links 8 and 8' pivoted at the ends thereof which are also pivoted to the levers 9 and 10 as clearly shown in Fig. 1. The levers are pivoted to a part of the machine frame at 11 and 12 respectively and carry arms 13 and 14 on which rollers 15 and 16 are revolvably mounted. The rocker arm 6 is operated by a revolving cam and connecting mechanism (not shown) but which is clear-

ly shown and described in the co-pending application aforesaid. Rocking movement 55 of the arm 6 causes oscillatory movement of the levers 9 and 10 which in turn cause vertical reciprocating or oscillatory movement of the arms 13 and 14 as will be apparent from an inspection of the drawing. 60

A pair of gates 17 and 18 pivoted to the frame at 19 and 20 respectively are provided with springs 21 to keep the gates in contact with rollers 15 and 16. The gates are provided with cams 22 and 23 against 65 which the rollers contact during operation of the rocker arm 6 to swing the gates on their pivots. Upon return movement, or normal position of the rocker arm 6, the gates will be returned to normal or idle 70 position by the springs 21.

A three-arm bell crank 24 is pivoted to the bridge 5, at 25, and a link 26 pivoted to the bell crank is operated vertically by suitable means (not shown), but which is 75 clearly shown and described in the before mentioned copending application. A closing head support bracket 27 carries a face plate 27' which is securely fastened to the frame as shown. This bracket has fixed 80 thereto a pair of rods 28 upon which the closing head 29 is slidably mounted. A pin 30 fixed to the closing head supports one end of a link 31 which has its other end pivotally connected at 32 to the bell 85 crank 24. During vertical reciprocation of the link 26 the closing head 29 will reciprocate horizontally on the rods 28.

The closing head is provided with a blade 33 which enters into the end of the carton 34 90 to guide the main flap tip 36 on the main flap 35 as it is being pushed into the carton by the gate 17. A finger 37 fixed to the closing head and spaced from the blade 33, Fig. 1, keeps the carton from bulging or spreading 95 and in proper relation to the blade 33.

A second closing head 38 carrying a blade 33' and a finger 37' is slidably mounted on the rods 39 which are fixed to the supporting bracket 40. A closing head connecting link 100 or pitman rod 41, has one end thereof pivoted at 42 to the bell crank 24 and its other end pivoted to a pin 43 mounted in the closing head 38. The heads 29 and 38 operate towards and away from each other simultaneously through the parts just described to 105

fold the end flap 35 and insert the end flap tip 36 at each end of the carton 34.

Curved guides 44 and 45 are fixed to a part of the machine frame adjacent the gates to 5 guide the carton end flap and to fold the end flap tip in proper position for insertion in the carton. These guides are provided with curved faces 46, 46' to guide the flap and to permit swinging movement of the gates and 10 are open at their outer ends to allow the gates to move freely. The ends of the gates extend beyond the guides but these ends are provided with slots 17' and 18' in which the guides are positioned, thus permitting the 15 gates to swing without interference with the guides.

The carton having been otherwise folded, the operation of folding the end flaps and tips by my improved mechanism is as follows: The carton 34 and its contents are moved along the guideways 47 and 48 to proper position where the end flaps and tips are inserted in the carton. As the carton is moved to position the flap tips will engage 25 the faces 46 and 46' on the guides 44 and 45 and the rocker arm 6 will operate to move the arms 13 and 14. The rollers 15 and 16 will then bear on the cams 22 and 23 and swing the gates 17 and 18 towards the end of 30 the carton. During this movement of the gates the closing heads 29 and 38 will move inwardly and the blades 33 and 33' will enter the carton to guide the end flap tips. The 35 gates move the end flaps tight against the carton and the guides 44 and 45 keep the tips in proper inserting position so that they may readily enter the carton. After this operation the arms and the closing heads are then returned to normal position and the 40 springs pull the gates away from the carton. The carton is then completely folded and ready to be removed from the guideways 47 and 48.

My novel folding mechanism for cartoning machines will quickly and positively close the end flaps of cartons and insert the flap tip into the carton in a new and novel manner, and the carton will be prevented from moving or becoming mutilated during 45 the folding operation.

I am aware that changes in the form, construction, and arrangements of the parts may be made without departing from the scope or spirit of the invention and I reserve the

right to make all such changes as fairly fall 55 within the scope of the following claims.

I claim:

1. Mechanism for folding an end flap and inserting the end flap tip of a carton into the carton comprising curved guides for guiding 60 the end flaps and tips to proper position, pivotal gates adjacent said guides, cams on said gates, intermittently operated means contacting with said gates for operating the same, reciprocating blades adapted to enter 65 the carton for guiding said tip into the carton as said gates are being operated, and fingers movable with said blades for engaging the outside of the carton to prevent bulging thereof.

2. Mechanism for folding the end flaps and inserting the end flap tip of a carton into the carton comprising curved guides for guiding the end flaps and tips to proper position, pivoted gates adjacent said guides for 70 folding the end flaps and tips to final position, cams on said gates, intermittently operated means including rollers operating on said cams for swinging said gates, reciprocating means including blades for guiding the 75 end flap tips into the carton, and fingers carried by said last named means for keeping the carton in proper position during return movement of said last named means, and means for retracting said gates as said last 80 named means returns to normal position.

3. Mechanism for folding the end flaps and inserting the end flap tips of a carton into the carton comprising curved guides for guiding the end flaps and tips to insertion 85 position, pivoted gates adjacent said guides adapted to bear against the end of the carton and carry the carton flaps and tips therewith, cams on said gates, intermittently operated means for operating gates, rollers on 90 said means and operating on said cams, intermittently reciprocating means operating simultaneously with said first named means, blades carried by said last named means for guiding the end flap tip into the carton as 95 the gates advance towards the carton, fingers for keeping the carton in position during return movement of said first named means, and means for returning said gates to normal 100 position during return movement of both of 105 said means.

ARTHUR H. BOILEAU.
